- ABSTRACT:** Adamantyl lactams are prepared by reacting an adamantyl amine with a 3-, 4-, or 5-halo acyl halide to yield an adamantyl amine haloamide followed by base cyclization of the latter. These adamantyl lactams possess antiviral and antibacterial activities.

N-ADAMANTYL AMIDES

This application is a continuation-in-part application of my copending application Ser. No. 837,000, filed 26 June 1969, now abandoned.

The present invention relates to adamantyl lactams.

It is an object of the present invention to provide adamantyl lactams having antiviral and antibacterial activity. Another object is to provide a method for the preparation of these compounds. A further object is to provide adamantyl amine haloamides which can be subjected to base cyclization to obtain the compounds of the present invention. These and other objects of the present invention will be apparent from the following description.

SUMMARY OF THE INVENTION

This invention relates to new compounds of the formula

(I)

wherein R and R' are the same or different and are H, lower alkyl or lower alkoxy, n is an integer from 0 to 4, and R'' and R''' are the same or different and are H, a straight or branched chain alkane of up to eight carbon atoms or a phenyl substituted alkane or a substituted-phenyl substituted alkane, of up to 10 carbon atoms, phenyl, or alicyclic of up to eight carbon atoms, and m is an integer from 1 to 3.

DETAILED DESCRIPTION

The compounds of the present invention are obtained by reacting a compound of the formula

(II)

wherein R and R' are the same or different and are H, lower alkyl or lower alkoxy, n is an integer from 0 to 4, with a halo-acyl halide of the formula

(III)

wherein X is Cl or Br and R'' and R''' are the same or different and are H, a straight or branched chain alkane of up to eight carbon atoms or phenyl substituted alkane or a substituted-phenyl substituted alkane, of up to 10 carbon atoms, phenyl, or alicyclic of up to eight carbon atoms, and s is an integer from 0 to 2.

For R and R', the lower alkyl groups include straight or branched chain aliphatic hydrocarbon radicals of up to six carbon atoms. Examples of such lower alkyl groups are the following radicals: methyl, ethyl, propyl, i-propyl, n-butyl, i-butyl, n-pentyl, neopentyl, 2-methyl-n-butyl, n-hexyl, 2-methyl-n-pentyl, 3-methyl-n-pentyl, 2,2-dimethyl-n-butyl, and 2,3-dimethyl-n-butyl. The lower alkoxy groups similarly include straight or branched chain aliphatic oxyhydrocarbon radicals containing up to six carbon atoms. Examples of such lower alkoxy groups are those corresponding to foregoing lower alkyl radicals.

For R'' and R''', the straight or branched chain alkane includes such groups as, for example, methyl, ethyl, n-propyl, i-propyl, n-butyl, i-butyl, n-pentyl, 2-methyl-n-butyl, neopentyl,

35

n-hexyl, 2-methyl-n-pentyl, 3-methyl-n-pentyl, 2,2-dimethyl-n-butyl, 2,3-dimethyl-n-butyl, n-heptyl, 2-methyl-n-hexyl, 3-methyl-n-hexyl, 2,2-dimethyl-n-pentyl, 2,3-dimethyl-n-pentyl, 2,4-dimethyl-n-pentyl, 3,3-dimethyl-n-pentyl, 3-ethyl-n-pentyl, 2,2,3-trimethyl-butane, n-octyl, 2-methyl-n-heptyl, 3-methyl-n-heptyl, 4-methyl-n-heptyl, 2,3-dimethyl-n-hexyl, 2,4-dimethyl-n-hexyl, 2,5-dimethyl-n-hexyl, 2,2-dimethyl-n-hexyl, 3,3-dimethyl-n-hexyl, 2-ethyl-n-hexyl, 3-ethyl-n-hexyl, 2,2,3-trimethyl-n-pentyl, 2,2,4-trimethyl-n-pentyl, 2,3,3-trimethyl-n-pentyl, 2,3,4-trimethyl-n-pentyl, 2-ethyl-3-methyl-n-pentyl, 2-methyl-3-ethyl-n-pentyl, and 2,2,3,3-tetramethyl-n-butyl. Alicyclic substituents for R'' and R''' include cyclopropyl, cyclobutyl, cyclopentyl, cyclohexyl, 1,1-dimethylcyclopropyl, 1-methyl-cyclohexyl, 1,2-dimethylcyclohexyl, cycloheptyl and cyclooctyl. Phenyl substituted alkanes include benzyl and phenethyl. The total number of carbon atoms in both groups R'' and R''', however, should not exceed about 12.

20 In the case of phenyl-substituted alkanes, the phenyl radical may itself be substituted by such groups as halogen, lower alkane and lower alkene, lower haloalkyl, lower alkoxy, lower alkylamino, nitro or cyano. Examples of some specific substituted phenyl radicals are: fluorophenyl, chlorophenyl, bromophenyl, iodophenyl, tolyl, trifluorotolyl, vinylphenyl, methoxyphenyl, ethoxyphenyl, propoxyphenyl, N-methyl anilino, N-dimethyl anilino, nitrophenyl and cyanophenyl.

The product obtained by reacting a compound of formula II with a compound of formula III is an adamantylamine haloamide of the formula

(IV)

30 40 wherein R, R', n, R'', and R''' and s are as defined above. Base cyclization of compound IV yields the compounds I of the present invention. Bases which may be used to effect cyclization include sodium in liquid ammonia; sodium hydride in dimethylsulfoxide; sodium hydride in dimethylformamide; potassium t-butoxide in toluene; and potassium t-butoxide in benzene.

45 The adamantyl amine compounds of formula II wherein n is other than 0 may be prepared by reduction of the corresponding amide with lithium aluminum hydride.

50 55 The adamantane carboxylic acid amide wherein n is 1 may be prepared by reacting 1-adamantane carboxylic acid with thionyl chloride to form the 1-adamantane acid chloride, and reacting the latter with ammonia to form the amide. The amide in turn is reduced, for example, by LiAlH₄ to the 1-adamantylmethylamine.

60 65 1-Adamantyl ethylamine wherein n is 2 may be prepared, for example, by reacting 1-bromoadamantane with 1,1-dichloroethylene in the presence of BF₃. The resulting 1-adamantyl acetic acid is then converted to the amide in the manner described above and the latter reduced, for example, by means of lithium aluminum hydride.

70 75 1-Adamantyl propylamine wherein n is 3 may be prepared, for example, starting from 1-adamantyl acetic acid, by homologation to 1-adamantyl propionic acid according to the method described by Bachmann et al., *Organic Reactions*, Vol. 1, Chapter 2, and then conversion to the corresponding amine as described above.

1-Adamantyl butylamine wherein n is 4 may be prepared, for example, in like manner starting with 1-adamantyl propionic acid.

Compounds of formula I wherein m is 1 may be prepared by reacting a compound of formula II with a 3-halo-acyl halide,

that is, a compound of formula III wherein *s* is 0 to form an adamantlyl amine haloamide followed by base cyclization of the latter. Compounds of formula I wherein *m* is 2 may be prepared by reacting a compound of formula II with a 4-haloacyl halide, that is, a compound of formula III wherein *s* is 1 to form an adamantlyl amine haloamide followed by base cyclization of the latter. Compounds of formula I wherein *m* is 3 may be prepared by reacting a compound of formula II with a 5-haloacyl halide, that is, a compound of formula III wherein *s* is 2 to form an adamantlyl amine haloamide followed by base cyclization of the latter.

The following examples illustrate the present invention without, however, limiting the same thereto.

EXAMPLE 1

1-Adamantylmethylamine

1. Preparation of 1-adamantane carboxylic acid chloride

To 18 g. of 1-adamantane carboxylic acid, 50 ml. of thionyl chloride is added with cooling, and the mixture is heated under reflux for 30 minutes. The excess thionyl chloride is removed in vacuo. Anhydrous ether is added and the solution evaporated leaving 19.2 g. (79.2 percent) of 1-adamantane carboxylic acid chloride as a brownish white solid; λ_{max}^{Nujol} 5.61 μ (C=O of acid chloride).

2. Preparation of 1-adamantanecarboxamide

1-Adamantane carboxylic acid chloride (35 g.) dissolved in 70 ml. of dry tetrahydrofuran, is added to a cooled aqueous ammonia solution. A white precipitate separates and the mixture is then stirred for 0.5 hours. The precipitate is filtered, washed with water and dried over P_2O_5 in vacuo to give 30.1 g. of 1-adamantanecarboxamide; m.p. 186-187.5 $^{\circ}$ λ_{max}^{Nujol} 5.95 μ (C=O of amide).

3. Preparation of 1-adamantylmethylamine

To a stirred suspension of 30 g. of lithium aluminum hydride in 1,000 ml. of ether, 27 g. (0.15 mole) of 1-adamantanecarboxamide is added in portions over a 1.5 hour period. The reaction mixture is stirred at room temperature for 1 hour, then refluxed with stirring for 4 hours and finally allowed to stand overnight at room temperature. The suspension is cooled and 50 ml. of water are added dropwise with stirring. This is followed by the addition of 100 ml. of 10 percent sodium hydroxide solution. The ethereal layer is separated and the solid is extracted three times with ether. The combined ethereal layer is dried and evaporated in vacuo to give 14.5 g. of 1-adamantylmethylamine as a pale yellow liquid.

EXAMPLE 2

2-(1-Adamantyl)-ethylamine

1. Preparation of 1-Adamantylacetic acid

A solution of 25 g. of 1-bromoadamantane in 100 g. of dichloroethylene is added dropwise over a 1.5 hour period to 100 ml. of 90 percent sulfuric acid containing 18 g. of boron-trifluoride while maintaining the temperature between 8-10 $^{\circ}$. The mixture is then stirred at 10 $^{\circ}$ for 3 hours, then ice and water are added. The crude precipitate is dissolved in 10 percent sodium hydroxide solution and the cloudy solution extracted with ether. The alkaline solution is cooled, acidified with 5 percent hydrochloric acid, and the precipitated 1-adamantylacetic acid collected and dried to give 21.5 g. of white solid, m.p. 130 $^{\circ}$ -133 $^{\circ}$.

2. Preparation of 1-Adamantaneacetic acid chloride

This is prepared in the same manner as 1-adamantane carboxylic acid chloride (example 1, 1) except that 1-adamantaneacetic acid is employed as the starting material.

3. Preparation of 1-adamantaneacetamide

This is prepared in the same manner as 1-adamantanecarboxamide (example 1, 2) except that 1-adamantaneacetic acid chloride is employed as the starting material.

4. Preparation of 2-(1-Adamantyl)-ethylamine

10 This is prepared in the same manner as 1-adamantylmethylamine (example 1, 3) except that 1-adamantaneacetamide is employed as the starting material.

EXAMPLE 3

N-(1-Adamantyl)-3-bromopropionamide

To 15.1 g. (0.1 mole) of 1-aminoadamantane dissolved in 500 ml. of dry benzene, a solution of 17.1 g. (0.1 mole) of β -bromopropionyl chloride in 50 ml. of dry benzene is added with cooling. The reaction mixture is stirred and refluxed for 2 hours. After cooling, the reaction mixture is washed with water, dilute hydrochloric acid, sodium bicarbonate solution, and water. The benzene layer is dried ($MgSO_4$) and evaporated to give an oily residue which solidifies on trituration with ether, 12.3 g., m.p. 131 $^{\circ}$ -133 $^{\circ}$. Crystallization from acetonitrile gives 8.3 g. of shiny white crystals, m.p. 134 $^{\circ}$ -135 $^{\circ}$; λ_{max}^{Nujol} 2.95 μ (NH), 6.05 μ (C=O).

EXAMPLE 4

1-(1-Adamantyl)-2-azetidinone

A suspension of 250 g. of sodium hydride in 10 ml. of dimethyl sulfoxide is stirred under nitrogen at 75 $^{\circ}$ for 1.5 hours. The mixture is cooled to 25 $^{\circ}$, and a solution of 500 mg. of N-(1-adamantyl)-3-bromopropionamide in 3 ml. of dimethyl sulfoxide is added dropwise. The mixture is stirred overnight at 35 $^{\circ}$, and then poured into water and extracted with ether. The ether extracts are washed with water, 8 percent salt solution, dried (Na_2SO_4) and evaporated to give an oily residue. Plate chromatography of the residue on silica gel using ethyl acetate as the developing solvent and elution of the more polar major product with ethyl acetate-methanol (4:1) gives 234 mg. of 1-(1-adamantyl)-2-azetidinone, λKBr 5.75 μ ;

TMS
 τ_{CDCl_3}

50 7.25 (q 3-CH₂) and 6.86 (q4-CH₂). The analytical sample is prepared by evaporative distillation to give an oil, which solidifies on standing, m.p. 43.5 $^{\circ}$ -45.5 $^{\circ}$.

EXAMPLES 5-48

The following adamantlyl and adamantlyl alkyl-3-halo propionamides are prepared by reacting the indicated adamantan derivative with the indicated 3-halopropionylhalide according to the procedure of example 3:

TABLE 1

Example	Adamantane derivative	3-halopropionyl halide	Product
5.	1-adamantylamine	3-bromopropionyl chloride	N-(1-adamantyl)-3-bromopropionamide.
6.	1-adamantylmethylamine	2-methyl-3-bromopropionyl chloride	N-(1-adamantylmethyl)-2-methyl-3-bromopropionamide.
7.	1-adamantylethylamine	2,2-dimethyl-3-bromopropionyl chloride	N-(1-adamantylethyl)-2,2-dimethyl-3-bromopropionamide.
8.	1-adamantyl-n-propylamine	2-ethyl-3-bromopropionyl chloride	N-(1-adamantyl-n-propyl)-2-ethyl-3-bromopropionamide.
9.	1-adamantyl-n-butylamine	2-methyl-2-ethyl-3-bromopropionyl chloride	N-(1-adamantyl-n-butyl)-2-methyl-2-ethyl-3-bromopropionamide.

TABLE 1—Continued

Example	Adamantane derivative	3-halopropionyl halide	Product
10.	1-adamantylamine	2,2-diethyl-3-bromopropionyl chloride	N(1-adamantyl)-2,2-diethyl-3-bromopropionamide.
11.	1-adamantylmethamphetamine	2-n-propyl-3-bromopropionyl chloride	N(1-adamantylmethyl)-2-n-propyl-3-bromopropionamide.
12.	1-adamantylethylamine	2-i-propyl-3-bromopropionyl chloride	N(1-adamantylethyl)-2-i-propyl-3-bromopropionamide.
13.	1-adamantyl-n-propylamine	2-methyl-2-n-propyl-3-bromopropionyl chloride	N(1-adamantyl-n-propyl)-2-methyl-2-n-propyl-3-bromopropionamide.
14.	1-adamantyl-n-butylamine	2-ethyl-2-n-propyl-3-bromopropionyl chloride	N(1-adamantyl-n-butyl)-2-ethyl-2-n-propyl-3-bromopropionamide.
15.	1-adamantylamine	2-ethyl-2-i-propyl-3-bromopropionyl chloride	N(1-adamantyl)-2-ethyl-2-i-propyl-3-bromopropionamide.
16.	1-adamantylmethylamine	2,2-di-n-propyl-3-bromopropionyl chloride	N(1-adamantylmethyl)-2,2-di-n-propyl-3-bromopropionamide.
17.	1-adamantylethylamine	2,2-di-i-propyl-3-bromopropionyl chloride	N(1-adamantylethyl)-2,2-di-i-propyl-3-bromopropionamide.
18.	1-adamantyl-n-propylamine	2-n-propyl-2-i-propyl-3-bromopropionyl chloride	N(1-adamantyl-n-propyl)-2-n-propyl-2-i-propyl-3-bromopropionamide.
19.	1-adamantyl-n-butylamine	2-n-pentyl-3-bromopropionyl chloride	N(1-adamantyl-n-butyl)-2-n-butyl-3-bromopropionamide.
20.	1-adamantylamine	2-n-pentyl-3-bromopropionyl chloride	N(1-adamantyl)-2-n-pentyl-3-bromopropionamide.

100.....	96	CH ₃	H	H	H	3	

The new products of the invention are useful as antiviral

agents, e.g., against influenza virus such as A-PR8 or hepatic virus such as MHV₃. They may be administered to a warm blooded animal in accordance with this invention by any convenient route, including orally, or parenterally, that is, subcu-

taneously, intravenously, intramuscularly, or intraperitoneally. Administration can also be by vapor or spray through the mouth or nasal passages.

The dosage administered will be dependent upon the age, health and weight of the recipient, kind of concurrent treatment, if any, frequency of treatment, and the nature of the effect desired. Generally, a daily dosage of active ingredient compound will be from about 1 to 200 milligrams per kilogram of body weight, although lower, such as 0.5 milligram, or higher amounts can be used. Ordinarily, from 1 to 50, preferably 1 to 20, milligrams per kilogram per day in one or more applications per day is effective to obtain the desired result.

The compounds of the present invention can be employed

in useful compositions according to the present invention by incorporating the free base or a physiologically acceptable salt thereof in such dosage forms as tablets, capsules, powder packets, or liquid solutions, suspensions, or elixirs, for oral administration, or liquid solutions for parenteral use, and in certain cases, suspension for parenteral use (except intravenous since, of course, intravenous suspensions of any material are hazardous). In such compositions, the active ingredient will ordinarily always be present in an amount of at least 0.0001 percent by weight based on the total weight of the composition and not more than 99 percent by weight.

Besides the compounds of the present invention, the composition will contain a solid or liquid nontoxic pharmaceutical carrier for the active ingredient. Mixtures with one or more pharmaceutically active materials can of course be used.

In one embodiment of a pharmaceutical composition of this invention, the solid carrier is a capsule which can be of the ordinary gelatin type. In another embodiment, the active ingredient is tableted with or without adjuvants. In yet another embodiment, the active ingredient is put into powder packets. In these capsules, tablets, and powders the pharmaceutical carrier will generally constitute from about 5 percent to about 95 percent and preferably from 25 percent to 90 percent by weight. These dosage forms preferably contain from about 5 to 500 milligrams of active ingredient with from about 25 to 250 milligrams most preferred.

The pharmaceutical carrier can, as previously indicated, be a sterile liquid such as water and oils, including oils of petroleum, animal, vegetable or synthetic origin, for example, peanut oil, soybean oil, mineral oil, cod liver oil, and the like. In general, water, saline and aqueous dextrose (glucose) and related sugar solutions are preferred liquid carriers, particularly for injectable solutions. Sterile injectable solutions will ordinarily contain from about 0.5 to 25 percent, and preferably about 5 to 10 percent, by weight of the active ingredient.

As mentioned above, oral administration can be in a suitable suspension or syrup, in which the active ingredient or-

dinarily will constitute from about 0.5 to 10 percent, and preferably about 2 to 5 percent, by weight. The pharmaceutical carrier in such composition can be a watery vehicle such as an aromatic water, a syrup or a pharmaceutical mucilage.

Suitable pharmaceutical carriers are described in REMINGTON'S PRACTICE OF PHARMACY by E. W. Martin and E. F. Cook, a well-known reference text in this field.

What is claimed is:

1. A compound of the formula

wherein

20 R and R' may be the same or different and may be H, lower alkyl or lower alkoxy;

n is an integer from 0 to 4;

25 R'' and R''' may be the same or different and may be H, a straight or branched chain alkyl radical of up to eight carbon atoms, a phenyl substituted alkyl radical, or a substituted-phenyl substituted alkyl radical having a total of 10 carbon atoms wherein the phenyl substituent may be halogen, alkyl, alkenyl, haloalkyl, alkoxy, alkylamine, nitro or cyano; phenyl; or alicyclic of up to eight carbon atoms;

s is an integer from 0 to 2; and

X is Cl or Br.

2. A compound according to claim 10, wherein s is 0.

UNITED STATES PATENT OFFICE
CERTIFICATE OF CORRECTION

Patent No. 3,624,124 Dated November 30, 1971

Inventor(s) Seymour D. Levine and Venkatachala L. Narayanan

It is certified that error appears in the above-identified patent and that said Letters Patent are hereby corrected as shown below:

Column 2, line 16, "an" should read -- and --. Column 7, lines 1-4, should be deleted and should be inserted before line 58.

Signed and sealed this 13th day of June 1972.

(SEAL)
